GRINDING MACHINE

Fernand Turrettini, Bellevue-Geneva, Switzerland, assignor to Societe Genevoise d'Instruments de Physique, Geneva, Switzerland, a firm of Switzerland

Application June 30, 1939, Serial No. 282,275
In Switzerland July 18, 1938

3 Claims. (Cl. 51—45)

The present invention relates to grinding machines and in particular to machines for grinding the threads of a workpiece as thread cutting tools and the like.

Certain types of grinding machines provide two cams, one of which is adapted to exert an effect upon the profile of the workpiece, which appears in the section through the axis of rotation of the workpiece, and the other cam is adapted to exert an effect upon the profile appearing in a perpendicular section relative to said axis of the workpiece, each cam acting upon the organ which regulates the distance between the axis of the grinding wheel and the axis of the workpiece by the intermediary of a slidable piece.

The object of the invention is, on the one hand the provision, of two reduction devices, each of which is constituted by an inclined plane member of micrometrically adjustable inclination and associated to one of said cams, and on the other hand, the provision of a hinged roller system, which is operable by means of said slidable piece for rolling on said plane members and bearing against said organ which regulates the distance between the two axes of the grinding wheel and the workpiece, respectively, so as to move this organ when the hinged roller system rolls on the inclined plane members.

The invention consists furthermore in the construction and arrangement of certain parts as will be apparent from the following description and claims, reference being had to the accompanying drawings which show one embodiment of the present invention.

In the drawings:

Figure 1 is a plan view of the embodiment, partly drawn in section, illustrating a screw thread grinding machine according to the invention.

Figure 2 is a lateral elevation thereof, partly drawn in section.

Figure 3 shows a modified detail of the machine.

The represented machine is adapted to grind screw taps, thread milling cutters and like thread cutting tools. It comprises two tables 16 and 33, the first one 16 being slidable along the guideways 15 of the machine bed, and the second one 33 being slidable in perpendicular direction to the first table along the guideways 33a. The table 33 which carries the bearings wherein a cutting organ constituted by the grinding wheel 21 can rotate is rigidly coupled to a rod 32 for being thereby moved under the action of a servomotor 31. The table 16 carries a spindle head 9 provid-

ing the rotatable center, and a tailstock 17 providing the back center 8a, between which centers the workpiece 20 is mounted for rotation. On the axle of the back center 8a is arranged an adjustable truing tool 40 for truing the profile of the grinding wheel 21. This tool may be a diamond for instance, or an abrading point of harder material than that of the grinding wheel. The drive shaft 1 is mounted in bearings integral with the machine bed and can be operated by a not represented motor, by the intermediary of the pulley 2. The rotation of this shaft 1 is transmitted upon the spindle 8 in the spindle head 9 by means of a chain 10 driven by a sprocket wheel 15 slidably keyed on the shaft 1. By means of gear wheels 11 and 12 the spindle 8 is connected to the lead screw 13 journalled in the table 16 and turning in a nut 14 which is secured to the machine bed 15, whereby the ratio of said gear wheels can be adapted to the desired pitch of the thread of the workpiece 20. The shaft 1 drives furthermore, by the intermediary of the gear wheels 4, 5, 6 and 7, a shaft 3 carrying two cams 18 and 19 and rotating with the same speed as the spindle 8.

The cam 18 is provided for generating the profile of the workpiece, which would clearly appear in a section along the geometric axis of the workpiece, that is to say the screw thread profile, while the cam 19 is provided for generating a profile in a plane perpendicular to the axis of the workpiece, which can be the concentric profile of an ordinary screw, for instance, or the relieved profile of a screw tap.

The device connecting one or the other of cams 18 and 19 in operative relation with the servomotor 31 comprises an axially slidable rod 97 carrying two rollers 98 and 99 disposed on the same side of the rod and being adapted to be put into contact with the corresponding cam, either the first roller 98 with the cam 18 or the second roller 99 with the cam 19. Two plane members 107 and 108 following each other in the direction of axial displacement of the rod 97 have their plane surfaces vertically arranged and adjustably inclined with respect to said axial direction of the rod. A vertical support 114 being integral with the machine bed separates the two members and forms a certain alignment with their plane surfaces. The ends of the two members, which are adjacent to this support, are rotatably mounted in 111 and 112, respectively, on the machine bed, whereas the other free ends abut each against the end of a micrometer screw 109, respectively 110. These two screws permit

the accurate adjustment of the inclinations of the plane members. Opposite to these members is disposed a plate 113 which is integral with the rod 32 forming the leading organ of the servomotor. The latter receives the necessary force for moving the table 33 from pressure fluid arriving through a pipe 35 and leaving by pipe 36. The rod 97 carries at the right end a hinged parallelogram 101 which in turn carries two rollers 102 and 103. When the rod 97 reciprocates, this parallelogram is moved in the passage formed by the inclined member 107 or 108 and the plate 113, whereby the roller 102 co-operates with the plane surface of a member, while the roller 103 co-operates with the surface of the plate. Finally, the rod 97 carries two fixed collars 104 and 105, spaced from each other, and therebetween two discs 106 and 119 slidable on the rod and adapted to abut against the collars. A coil spring 120 is disposed between the two discs and all three parts are located in a casing 100 which can be displaced along guideways by means of the handle 100a. The two ends of the casing penetrated by the rod give free passage for the collars, but stop the slidable discs which can abut against said ends.

In the position shown in the drawings the spring 120 bears, on the one hand, by the intermediary of the disc 119, against the right end of the stationary casing 100 and, on the other hand, by the intermediary of the disc 106 against the collar 104, so that the roller 99 is continually applied against the cam 19. Under the action of the rotating cam 19 the hinged system 101 is displaced along the inclined plane member 107 wherethrough the plate 113 is subjected to a displacement which is perpendicular to that one of the rod 97, and which produces by the intermediary of the servo-motor 31 a corresponding displacement of the table 33. There is an intermediate position of the rod 97 wherein none of the rollers 98 and 99 registers with its cam; in this case the spring 120 which is initially tensioned, expands between the two collars 104 and 105. If the casing 100 is then shifted to the right, the spring 120 bears with the disc 106 against the left side of the casing and with the disc 119 against the collar 105 and applies the roller 98 against the cam 18. At the same time the hinged system 101 co-operates by means of the roller 102 with the plane surface of the inclined member 108.

The performance of the machine is the following: The table 16 is moved in order to bring the truing tool 40 into opposition with the grinding wheel 21. Then the servo-motor 31 is submitted to the action of the cam 18 and the pulley 2 is thrown into gear. The spindle 8 and the workpiece 20 begin to rotate while the table 16 moves over a determined length according to the ratio of the gear wheels 11 and 12. The table 33, and the grinding wheel therewith, moves in the guideways 33a under the action of the servo-motor 31 which is operated by the cam 18. By this truing procedure the grinding wheel 21 is provided with the exact profile. Afterwards the pulley 2 is disengaged, the table is moved so that the workpiece 20 comes opposite the grinding wheel 21, and the servo-motor is submitted to the action of the cam 19. When the pulley 2 is re-engaged, the accurately trued grinding wheel 21 generates the desired profile on the workpiece while the reciprocating motion imparted to the carriage of the grinding wheel produces the relieving of the

threads if the workpiece is a tool as a screw tap or a thread milling cutter. For grinding screw threads without the relieving the action of the servo-motor 31 is stopped by shifting the spring casing 100 into half-way position so that none of the rollers 98 and 99 registers with the corresponding cam.

The advantages of the above described machine are evident.

For generating a Whitworth thread of eleven threads per inch, for instance, the unique cam type for the Whitworth system is mounted on the shaft 3 of the machine, from which cam all the various Whitworth thread profiles can be derived, and the inclination of the plane member working in connection with this cam is adjusted in such a manner that the distance between the axes of the grinding wheel and the workpiece, respectively, is varied during one revolution of the latter for an amount which exactly corresponds with the depth of the Whitworth thread of eleven threads per inch.

As the lead screw 13 of the table 16 is connected with the spindle 8 entraining the workpiece 20, by means of the exchangeable reduction gear 11 and 12 which determines the pitch to be produced on the workpiece, the simultaneous effect of the axial displacement of the workpiece under the action of the lead screw, and of the perpendicular movement of the grinding wheel under the action of the cam and the variable reduction device will generate the desired thread profile which, at first, can be reproduced on the grinding wheel 21 by means of the truing tool 40, and then on the workpiece 20 by means of the trued grinding wheel.

If a metric thread (International system) with a pitch of two millimeters, for instance, is concerned, the procedure is exactly the same as above: The unique cam type for the International system is mounted on the machine and the variable reduction device is adjusted in order to generate the depth of the thread of a two millimeter pitch.

The second cam acts upon the radial section of the workpiece, that is to say, it is used to generate the relieving of the threads of screw taps or thread milling cutters. The number of the flutes of the tap are determined by the number of recesses on the drive of this second cam and the depth of the relieving is determined by the adjustment of the variable reduction device acting in connection with this cam.

The number of cams which are necessary for giving the predetermined thread to a workpiece is thus limited to a minimum, because all the treads of different pitches of a same thread system are obtained, with respect to their profiles appearing in an axial section, by a single cam type and all the depths of the relieving corresponding to a determined number of flutes of a tap are obtained by a single cam type having the same number of recesses. Finally, the fact that there is a variable reduction device for each cam facilitates the passage from one cam to the other and avoids that they are put out of adjustment during the performance of the truing or the relieving work.

In the modification of Fig. 3 the rod 97 is hingedly connected by the piece 118 to a frame 115 which is slidable in two bearings 116 and 117 on the machine bed and which carries the hinged parallelogram 101.

I claim:

1. In a grinding machine, in combination a

machine bed, displaceable means on said bed for supporting and rotating the work piece, a grinding wheel rotatably mounted on said machine bed, means for reciprocating either the work piece or grinding wheel in a transverse movement perpendicular to the axis of rotation of the other not reciprocated part, a reciprocatable organ controlling the said transverse movement, an adjustable wheel profiling tool mounted for displacement with the work piece, a rotatable cam system comprising two different cams, two reduction devices each one being constituted by an inclined plane member of micrometrically adjustable inclination, a slideable rod adapted to cooperate alternatively with one and the other of said cams, and a hinged roller system on said rod adapted to bear on said inclined plane members on one side and against said reciprocatable organ on the other side, said cams being alternatively adapted to reciprocate said organ by the intermediary of said rod and hinged roller system so as to accomplish the dual function of, first generating by means of said profiling tool the profile of the grinding wheel in a section along the axis of the work piece and, second generating by means of said wheel the profile of the work piece in a section perpendicular to the axis of said piece.

2. In a grinding machine, in combination a machine bed, displaceable means on said bed for supporting and rotating the work piece, a grinding wheel rotatably mounted on said machine bed, a servo-motor having a reciprocatable organ for reciprocating said grinding wheel in a transverse movement perpendicular to the axis of rotation of the work piece, an adjustable wheel profiling tool mounted for axial displacement with the work piece, a rotatable cam system comprising two different cams on a common axle, means for imparting rotation to the work piece and cams and effecting axial displacement of work piece and profiling tool, means for varying the rate of said displacement, two reduction devices, each one being constituted by an in-

clined plane member of micrometrically adjustable inclination, a rod carrying two rollers adapted to cooperate each with one of said cams, said rod being capable of sliding movement to and fro for bringing each of said rollers alternatively into contact with the cooperating cam, and a frame connected to said rod and carrying a hinged roller system adapted to bear on one or the other of said inclined plane members on 10 one side and against said reciprocatable organ on the other side, said cams being alternatively adapted to reciprocate said organ by the intermediary of said rod, frame and hinged roller system, when said roller system bears on said 15 inclined plane members, so as to accomplish the dual function of, first generating by means of said profiling tool the profile of the grinding wheel in a section along the axis of the work piece and, second generating by means of said wheel the profile of the work piece in a section 20 perpendicular to the axis of said piece.

3. Grinding machine according to claim 2 for generating the relieved threads of thread cutting tools, one of said cams being so constructed as to reproduce on the grinding wheel, by means of 25 the profiling tool and in cooperation with one of the rollers on said slideable rod, one of said adjustable reduction devices and the reciprocatable organ of said servo-motor the longitudinal profiles of all thread sizes of a same thread system, and the other of said cams being provided 30 with recesses so as to generate the profile on the work piece, by means of said grinding wheel and, simultaneously in cooperation with the other roller on said slideable rod, the other reduction device and the reciprocatable organ of said 35 servo-motor the relieving of the threads, the number of flutes being determined by the number of recesses on said other cam and the depths 40 of the relieving obtained by the adjustment of the said other reduction device acting in connection with said cam.

FERNAND TURRETTINI.
